UNITED STATES PATENT OFFICE.

GEORGE P. WEBSTER, OF SEATTLE, WASHINGTON.

VALVE-SPRING-COMPRESSING CLAMP.

1,374,694.

Specification of Letters Patent. Patented Apr. 12, 1921.

Application filed January 2, 1920, Serial No. 348,865. Renewed January 27, 1921. Serial No. 440,537.

To all whom it may concern:

Be it known that I, GEORGE P. WEBSTER, a citizen of the United States, residing at Seattle, in the county of King and State of Washington, have invented certain new and useful Improvements in Valve-Spring-Compressing Clamps, of which the following is a specification.

My invention relates to improvements in valve spring compressing clamps of the form commonly known as valve lifters that are adapted to be used for compressing the springs on the valves of internal combustion engines preparatory to removing such valves from an engine.

The object of my improvement is to provide a valve spring compressing clamp that is simple and durable in construction, that may be quickly and easily manipulated either to clamp or to release a valve spring and that has few parts and is relatively cheap to construct.

Another object is to provide a valve spring compressing clamp of this nature having a novel and efficient lever arrangement for imparting movement to a main thrust bar and having quickly releasable ratchet means for holding such thrust bar in any depressed position.

A still further object is to provide a peculiarly shaped clamp frame that is particularly well adapted to be used in locations that are difficult of access as for instance on V type motors.

The invention consists in the novel construction, adaptation and combination of parts of a valve spring clamp as will be more clearly hereinafter described and claimed.

In the accompanying drawings Figure 1 is a view in side elevation of a clamp constructed in accordance with my invention. Fig. 2 is a plan view of the same. Fig. 3 is a view in elevation with one of the side plates removed of the head portion of the clamp. Fig. 4 is a view partly in plan and partly in cross section substantially on a broken line 4, 4 of Fig. 1 and Fig. 5 is a view in side elevation on a reduced scale of the clamp as it may appear when applied to a valve in a V type engine, a portion of the engine being shown in elevation and a portion being shown in cross section.

In removing valves from internal combustion engines it is necessary to compress the valve springs and to hold such valve

springs under compression while certain locking devices on the lower ends of the valve stems are being removed preparatory to taking out the valves. The springs of these valves are relatively strong and are often located in positions difficult of access so that the removal of the valves requires the expenditure of considerable time and labor if attempted without the use of tools that are especially constructed for that purpose. My valve spring compressing clamp is designed to reduce the amount of labor and shorten the length of time required for removing valves and is so constructed that it may be used on the valves of practically any of the ordinary types of internal combustion engines, including engines of the V type on which the valves are particularly inaccessible.

Referring to the accompanying drawings, throughout which like reference numerals designate like parts, I have shown a clamp frame comprising a normally horizontal top portion 6, a normally vertical side portion 7 and inclined lower side portion 8 and a normally horizontal bottom portion 9, the frame portions 6, 7, 8 and 9 forming a clamp frame which is substantially rectangular except for the beveled corner formed by the portion 8.

The forward end of the lower frame portion 9 is provided with forked or bifurcated foot member that is formed by cutting away the lower portion of the front end of the frame bar 9 as shown in Fig. 1, then bending such end to one side of the center as shown at 10 in Fig. 4 and then riveting a separate piece 11 of substantially the same shape as the bent end portion 10 to frame member 9 so that the portions 10 and 11 constitute a symmetrical forked foot member that is adapted to fit over the stem 12 of a valve member 13 in an engine 14 as indicated in Fig. 5.

The upper portion 6 of the clamp frame has plates 15 and 16 secured to the opposite sides thereof by means of rivets 17 which pass through the plates and through the clamp frame.

The plates 15 and 16 project forwardly from the end of the frame portion 6 and are supported in spaced apart relation by blocks or shims 20 and 21 which cooperate with the plates 15 and 16 to form a guideway 22 for a movable clamping bar 23, the plates 15 and 16 and the blocks 20 and

21 being rigidly secured together by rivets 17. The plates 15 and 16 are provided on their front edges with forwardly projecting lugs 24 through which extends a transverse pivot 25 upon which is fulcrumed the lower end of a link 26. The upper end of the link 26 is connected by a pivot 27 with the end of a lever arm 28, which lever arm 28 is secured by a pivot 30 to the top end of the 10 clamp bar 23, the arrangement being such that when the lever arm 28 is moved up and down the clamp bar 23 will be moved lengthwise within the guideway 22. The link 26 forms a movable fulcrum for the lever arm 28 and permits the clamp bar 23 to be moved without binding in response to oscillation of the lever arm.

The bottom end of the clamp bar 23 is preferably pointed as at 31 to engage within 20 a centrally located recess which is usually provided in the top side of the valves of internal combustion engines.

The rear edge of the clamp bar 23 is provided with ratchet teeth 32 that are adapted 25 to be engaged by the end of a slidably mounted pawl or bar 33 which is disposed directly below the frame portion 6 and is guided for longitudinal movement by a clip 34 and by the block 21, the upper end of the 30 block 21 being spaced a short distance below the bottom edge of the frame portion 6.

The bar 33 is urged forwardly into engagement with the ratchet teeth 32 by a helical tension spring 35 that is connected 35 with the bar 33 and with a transverse rivet 36 that extends through the plates 15 and 16.

The outer end of the bar 33 is turned downwardly as at 37 to form a finger hold by means of which the bar may be withdrawn 40 from engagement with the ratchet teeth 32, the downwardly projecting portion 37 being near enough to the vertical portion 7 of the clamp frame so that both of these parts may be grasped simultaneously and the bar 45 33 moved by exerting a squeezing movement with the hand.

In operation after the necessary parts of the engine have been removed so that access to the valves may be had the bifurcated foot 50 formed by the portions 10 and 11 is inserted beneath a washer 38 that supports the outermost end of a valve spring 40, the lever 28 is raised far enough to permit the clamping bar 23 to enter the upper end of the cylinder block and the lever 28 is then depressed thereby causing the clamping bar 23 to engage with the top side of the valve 13 and the foot to lift the washer 38 and compress the spring 40, thereby permitting the removal 55 of a stop 41 on the valve stem so that when the spring compressing clamp is released the valve may be lifted out of the motor. The clamp is used in a similar manner for compressing the springs when the 60 valves are replaced.

The pawl 33 by its engagement with the teeth 32 serves to hold the springs in any compressed position and may be quickly and easily released by the operator.

The peculiar shape given to the clamp 70 frame by the angular corner portion 8 enables my device to be used on several types of motors where a rectangular frame or a C shaped frame could not be used, as for instance on the V type motor shown in Fig. 75 5 where the angular corner avoids interference with the block of the twin cylinder opposite the one from which the valve is being removed and also avoids interference with the exhaust pipe 42 of such cylinder 80 and still allows the clamp frame to be so formed as to provide ample room in the upper portion thereof.

It will be understood that changes in the form, dimensions and arrangement of parts 85 of this device may be resorted to within the scope of the claims.

What I claim is:

1. A valve spring compressing clamp comprising an open clamp frame having a straight top side, a forked foot on the lower extremity of said clamp frame, guiding means at the upper extremity of said clamp frame, a clamp bar guided by said guiding means for movement toward and away from said foot, said clamp bar having ratchet teeth formed in the rear edge thereof, a spring pressed pawl guided for movement along the lower edge of said straight top frame portion and arranged to yieldingly 100 engage said teeth to prevent movement of said bar away from said foot member, a downwardly projecting finger hold on the outer end of said pawl and devices for moving said clamp bar within said clamp frame. 95

2. A valve spring compressing clamp comprising an open clamp frame having a straight top side, a forked foot at the bottom extremity of said clamp frame, plates 110 secured to opposite sides of the upper extremity of said clamp frame and projecting forwardly therefrom to form a guideway, a clamp bar movable lengthwise within said guideway, ratchet teeth formed on the rear edge of said clamp bar, a link pivoted to said plates, a lever arm fulcrumed on the upper end of said link and pivotally connected with the top end of said clamp bar, and a spring pressed pawl member guided for movement along the lower edge of the straight top side of said clamp frame and arranged to engage with the ratchet teeth of the said clamp bar, said pawl having its outer end bent downwardly to form a finger- 115 hold. 120

3. A valve spring compressing clamp comprising an open clamp frame having a straight top side, a forked foot at the bottom extremity of said clamp frame, plates 130

secured on opposite sides of the upper extremity of said clamp frame and projecting forwardly therefrom, a spacing block secured between said plates and coöperating 5 with said plates and said clamp frame to form a guideway, another spacing block secured between said plates below the end of said clamp frame and spaced slightly from said clamp frame, a clamp bar movable lengthwise within said guideway, 10 ratchet teeth formed on the rear edge of said clamp bar, a link pivoted to the front edges of said plates, a lever arm fulcrumed on the upper end of said link and pivotally connected with the top end of said clamp 15 bar, and a spring pressed pawl disposed directly below and movable lengthwise along said straight top side to engage the ratchet teeth on said clamp bar and normally prevent upward movement of said clamp bar, 20 said pawl having a downwardly projecting fingerhold.

Signed at Seattle, Washington, this 24th day of December, 1919.

GEORGE P. WEBSTER.
